UNITED STATES PATENT OFFICE.

THOMAS EDGAR REESE, OF BALTIMORE, MARYLAND.

TRANSFER HOLDER.

Application filed January 8, 1925. Serial No. 1,291.

This invention relates to certain improvements in transfer holders and it is an object of the invention to provide a device of this kind which will expedite the issuance 5 of transfers, checks and duplex receipts at all periods especially during rush hours.

Another object of the invention is to provide a device of this kind which will effectively hold for distribution any pad or 10 pack of transfers, checks and duplex receipts and which is particularly designed to be secured to fare box carriers now generally employed by transportation companies.

The invention consists in the details of 15 construction and in the combination and arrangement of the several parts of my improved transfer holder whereby certain important advantages are attained and the device rendered simpler, less expensive and 20 otherwise more convenient and advantageous for use, as will be hereinafter more fully set forth.

The novel features of my invention will 25 hereinafter be definitely claimed.

In order that my invention may be the 30 better understood, I will now proceed to describe the same with reference to the accompanying drawing, wherein:

Figure 1 is a view in plan illustrating a 35 blank from which my improved holder is produced;

Figure 2 is a view in side elevation of the 40 device in applied position;

Figure 3 is a view in top plan of the device in applied position;

Figure 4 is a view in elevation of the holding spring for a pad or pack unapplied.

As particularly illustrated in Figure 1 45 of the accompanying drawing, my improved holder is formed from a single sheet of metal possessing a certain degree of inherent resiliency and in production it is to be understood that the device is to be of such size and configuration as may be necessary in accordance with the style of fare box carrier with which it is to be employed.

As herein disclosed, my improved holder 50 comprises a body plate 1 of requisite dimensions and configuration but herein disclosed as oblong in form and which has struck from the opposite end portions thereof at its transverse center the oppositely directed tongues 2 and 3, the free ends of which being outwardly disposed. These tongues are 55 adapted to engage the bars *a* of the frame comprised in a fare box carrier or rigging.

At one end, the body plate 1 at substantially its transverse center is provided with a lug 4 which in the complete device, as illustrated in Figure 3, extends outwardly 60 at right angles to the plate 1 and terminates in an inwardly disposed extension 4', said extension 4' being spaced from the plate 1 to snugly receive thereunder an end portion of the cardboard back constituting the 65 bottom of all pads or packs of transfers or the like.

At substantially its longitudinal center, the plate 1 is provided with the outstanding 70 relatively short flanges or lugs 5 which constitute guards to provide further means for maintaining a pad or pack in desired applied position.

The opposite end of the plate 1 and at opposite sides of its transverse center is provided with the lugs 6 which are disposed 75 outwardly substantially at right angles to the plate 1 and terminate in the inwardly directed extensions 6'. These extensions 6' are forced into the stub end of the pack or 80 pad of transfers or the like to further assure the maintenance of such pack or pad in applied position.

The end of the plate 1 adjacent to the 85 lugs 6 has extending upwardly from its side margins the upstanding flanges or wings 7 with which are adapted to be hooked or otherwise engaged the extremities of the retractile member 8 preferably a spiral spring. This spring is adapted to be disposed over 90 the stub end portion of the applied pack or pad and exerts sufficient tension thereon to firmly hold the stub portion of the pad or pack.

From the foregoing description it is 95 thought to be obvious that a transfer holder constructed in accordance with my invention is particularly well adapted for use by reason of the convenience and facility with which it may be assembled and operated, 100 and it will also be obvious that my invention is susceptible of some change and modification without departing from the principles and spirit thereof and for this reason I do not wish to be understood as limiting 105 myself to the precise arrangement and formation of the several parts herein shown in carrying out my invention in practice except as hereinafter claimed.

I claim:

A holder of the class described comprising 110 a body plate, an outstanding lug car-

ried by an end portion of the plate, and having its free extremity inwardly disposed, a pair of lugs carried by the opposite end of the plate and at opposite sides of its transverse center, said second lugs also having their free extremities inwardly disposed, outstanding guard flanges carried by the side portions of the plate at the central part thereof, additional outstanding flanges carried by the side portions of the plate adjacent to the end provided with the two lugs, and

a retractile member adapted to be disposed transversely across the plate and engaged with said second named flanges, the body of the plate at the opposite end portions thereof and at substantially its transverse center having struck therefrom oppositely directed tongues, the free end portions of said tongues being outwardly disposed to provide an attaching medium.

THOMAS EDGAR REESE.
